UNITED STATES PATENT OFFICE.

JOHN P. FLETCHER, OF THE UNITED STATES ARMY.

JUNCTION BOX.

Application filed September 21, 1922. Serial No. 589,640.

(FILED UNDER THE ACT OF MARCH 3, 1883. 22 STAT. L., 625.)

To all whom it may concern:

Be it known that I, JOHN P. FLETCHER, major, Medical Corps, United States Army, and resident of Carlisle, in the county of Cumberland and State of Pennsylvania, have invented a new and useful Improvement in a Junction Box, of which the following description, in conjunction with the accompanying drawings, is a specification.

10 The invention described herein may be used by the Government, or any of its officers or employees in prosecution of work for the Government, or by any other person in the United States, without payment of any royalty thereon.

15 This invention generically relates to electrical distribution, more particularly it is directed to a new and improved junction box, designed especially for military usage in the field.

20 One of the principal objects of this invention is to produce a simple, compact and effective means, in the nature of a junction box, to facilitate the distribution of electrical energy in military encampments, evacuation hospitals and similar units.

25 Another important feature of this invention is the production of a device which will materially expedite utilization of surface cables, in the distribution of electrical energy from the source of supply to point of ultimate consumption.

30 Another purpose of this invention is to design a junction box of the character specified, accommodating a number of leads and having facilities to enable rapid union of their terminals.

35 Other objects of this invention are; to provide a junction box affording ready access to its interior, for inspection or other purposes and one which is weather-proof and suitably drained to preclude the possibility of accumulated water, producing a short circuit.

40 With these and other objects in view, this invention consists in certain novel details of construction, combination and arrangement of parts to be more fully hereinafter set forth and claimed.

45 Briefly stated this invention embodies a housing and hinged cover, the housing and cover having complementary portions, functioning when united to produce oppositely disposed elbow-shaped cable inlets and ex-

its, a terminal block located interior of the housing, suitably spaced binding post secured to and arising from the terminal block, an insulating baffle plate intermediate the binding post and means removably connected with the housing to enable its position upon a stake or like element.

Referring more particularly to the accompanying drawings in which similar parts are indicated by corresponding reference characters:

Fig. 1 is a sectionized side elevation, partly broken away, of the junction box constituting the subject matter of this invention.

Fig. 2 is a top plan partly broken away, showing cable leads in dotted outline, and

Fig. 3 is an end elevation also partly broken away.

In modern warfare, it is essential to the comfort and convenience of army units in the field, to provide, whenever possible, electrical energy for lighting and other purposes, and in doing so perhaps the evacuation hospital, presents the most difficult problem, owing to its kaleidoscopic nature.

Functionally an evacuation hospital has three activities, sorting, evacuation and hospitalization and according to what is considered the most ideal arrangement embodies approximately 750 beds assembled under 61 hospital ward tents which occupy a site of approximately 600 feet wide by 400 feet deep. In actual service, however, the occasions are few when the evacuation hospital can be assembled pursuant to this ideal arrangement, owing to the difficulty in securing the proper terrain and because its functions may vary according to the locality.

When laying out an electrical lighting system for such a hospital two factors are of prime importance namely; flexibility and elasticity, to permit alterations commensurate with the ever changing nature of these units.

With respect to the electrical installation within the tents, this is comparatively simple, the difficult problem, being the delivery of power from its source to the ultimate point of consumption, which may be accomplished by overhead, surface or underground lines.

Regarding overhead power transmission,

this is objectionable, because of the vast amount of material in the nature of poles, cross arms, insulators etc., which must be ported and would only serve to augment, 5 the already heavy burden of transportation imposed upon the Army in the field.

Underground transmission of power is likewise undesirable owing to the heavy and expensive cables, required, the difficulties attending attachment of distributing leads and the many provisions which must be made to provide suitable insulation for the buried cables. 10

In view of these objectionable features 15 rendering the overhead and underground system of power transmission unsatisfactory for military purposes, distribution by surface cable has been largely resorted to as the system most practical, economical and 20 best suited to meet the emergency requirements of the field, as the power cable may be laid directly upon the ground, except at points where it crosses the road or is otherwise exposed and at such places it may be laid in easily excavated shallow trenches.

As the system of electrical distribution designed for an evacuation hospital usually functions but once and must be modified to meet the requirement of each hospital unit, it has been found advantageous to divide the power lines into standard units of the most adaptable lengths and to provide at the junction of these units, a junction box from which leads may be taken to any desired point.

In the illustrated embodiment characterizing this invention, there is shown a metallic housing (10) apertured at its bottom as at (11) to provide suitable drainage of accumulated water. Central of the housing and in the bottom thereof is formed an annular internally threaded socket (12) for reception of an externally threaded sleeve (13) adapted to telescopically engage the 45 end of a stake or similar element, which may be driven into the ground at any desired location in the field.

To permit securement of the housing to a wall, ceiling or floor of a building it is 50 provided with laterally extending lugs (15) apertured as at (16) for the passage of suitable fastening elements. The housing (10) is closed and rendered weather proof by a cover (17) hinged as at (18) and secured 55 in this position by a suitable locking arrangement such as the hasp (19) and pad lock (20). Cover (17) is formed with a flanged edge (21) which when the cover is in closed position overlies the edge of the housing as clearly shown in Figure 3 of the drawing.

The cover (17) and housing (10) are formed at their ends with complementary 60 portions (22) which when united constitute curved elbows (22') through which the

cables pass to and from the binding post (hereinafter mentioned) situated interior of the housing.

Within the housing and surmounting the top wall of socket (12) is an insulating 70 block (23) secured in position by fastening elements (24). Arising from this block in parallel and laterally spaced relation are two binding posts (25) adapted to receive the terminals of the cable leads, which are 75 retained in position by wing nuts (26) in threaded engagement with the binding posts, as clearly shown in Figure 2 of the drawing.

Also secured to block (22) intermediate 80 the binding post (25) is a baffle plate (27) designed to serve as an insulating wall between the binding posts and leads to preclude the possibility of short circuiting.

Having described the structural details 85 of this invention, its operations is as follows:

Assuming the cover of the junction box to be in closed relation with respect to the housing, when it is desired to unite two 90 sections of cable, the cover is thrown back, exposing binding post (25), the eyelets of the supply and return leads of each cable section are then positioned upon the binding post, wing nuts (26) screwed down 95 and the union is thus quickly and expeditiously accomplished.

With an arrangement of this character it is apparent that numerous distributing 100 leads may be simultaneously accommodated, and connections made with the least possible delay.

In conclusion it will be seen this invention provides a device which materially expedites electrical distribution under emergency conditions and furnishes a simple, compact and efficient means for systems especially applicable to evacuation hospitals and similar Army units.

Although in the forgoing certain elements have been defined as best adapted to perform the functions allotted to them, nevertheless it is to be understood that various minor changes may be resorted to within the scope of the appended claims 110 115 without departing from or sacrificing any of the principles of this invention.

Having described my invention, what I claim as new and wish to secure by Letters Patent is:

1. A junction box comprising a housing, means in connection with the bottom of the housing to effect its securement to a wall or other flat surface and additional means removably associated with the bottom of the housing to telescopically engage the extremity of a stake or like element.

2. A junction box comprising a terminal housing, a cover hinged thereto, means in connection with the bottom of the housing 120 125

15

20

to effect its securement to a wall or other flat surface and additional means removably associated with the bottom of the housing to telescopically engage the extremity of a stake or like element.

3. A junction box comprising a housing, means in connection with the bottom of the housing to effect its securement to a wall or other flat surface and additional means 10 removably associated with the bottom of the housing to telescopically engage the extremity of a stake or like element, such means including a sleeve removably seated

in a socket formed in the bottom of the housing.

4. A junction box comprising a housing, anchoring elements extending laterally from the housing to effect its securement to a wall or other flat surface and additional means removably associated with the bottom of the housing to telescopically engage the extremity of a stake, such means including a sleeve removably seated in a socket formed in the bottom of the housing.

JOHN P. FLETCHER.
